UNITED STATES PATENT OFFICE.

ANDREW MILLER, OF CONNELLSVILLE, PENNSYLVANIA.

HOLDING AND RELEASING MECHANISM FOR BRAKE-SHAFTS.

No. 841,091.

Specification of Letters Patent.

Patented Jan. 8, 1907.

Application filed April 3, 1906. Serial No. 309,604.

To all whom it may concern:

Be it known that I, ANDREW MILLER, a citizen of the United States, residing at Connellsville, in the county of Fayette and State 5 of Pennsylvania, have invented a new and useful Improvement in Holding and Releasing Mechanism for Brake-Shafts, of which the following is a specification.

My invention relates to improvements in 10 pawl holding and releasing mechanism for brake-shafts.

The object of my invention is to provide a mechanism of this character whereby the pawl is readily moved in or out of engagement with the ratchet carried by the brake-operating shaft for releasing the same at any 15 time without moving the said shaft, which is usually necessary in brakes of the character to which my mechanism is to be applied.

Another object of my invention is to provide a more simple and effective mechanism to accomplish the above results without affecting the usual operation of the brake-shaft.

In the accompanying drawings, Figure 1 is a side elevation of my improved pawl-operating mechanism in combination with the ordinary brake-shaft as applied to a car. Fig. 2 is a top plan view showing the ratchet-operating lever in its normal position. Fig. 3 is a longitudinal vertical sectional view taken on the line $x-x$ of Fig. 2; and Fig. 4 is a sectional view similar to that shown in Fig. 3, with the pawl-carrying member thrown rearwardly and the pawl disengaged from the ratchet-disk.

Referring now to the drawings, 1 represents the platform or the top of a car, according to the character of the car to which my 40 device is applied, and 2 is the ordinary rotary brake-operating shaft, which has at its upper end a wheel or crank for operating the same and the lower end having the usual chain connection with the brake mechanism. Ad- 45 jacent to said shaft the platform or top, whichever it might be, is provided with an inverted-U-shaped frame 3, which is pro- vided with an outwardly-extending arm 4, forming a bearing for the shaft 2. The said 50 shaft above the arm 4 is provided with a ratchet-disk 5, having on its lower face ratchet-teeth 6. The said inverted-U-shaped frame has its upper end in a line with the upper face of the ratchet-disk, and pivoted 55 within said frame intermediate its ends at 7 is a pawl-carrying member 8, said member

being adapted to rock freely upon said pivot. The upper end of said pawl-carrying member extends upwardly adjacent to the upper end 9 of the frame 3, the said upper end of the 60 pawl-carrying member being bifurcated at 10, and intermediately pivoted within said bifurcated end is a pawl 11, normally in engagement with the teeth of the ratchet-disk. The opposite end of the pawl 11 is weighted 65 at 13 to hold the pawl in said engaged position. The rocking of the pawl-carrying member, as will be clearly seen, will move the pawl out of engagement with the ratchet-teeth, and in order to prevent the pawl from 70 moving upwardly beyond the ratchet-disk I provide the upper end 9 of the U-shaped frame with a beveled face or plate 14, against which the pawl rides and by means of which the pawl is guided in its proper position to 75 engage the ratchet-teeth.

The platform or top of the car, whichever the case may be, adjacent the frame 3 is provided with the two bearings 15 and 16, in which is journaled a shaft 17. The said 80 shaft intermediate the journals is provided with the double crank 18, to which is connected in the usual manner the pitman 20. The opposite end of said pitman 20 is bifurcated at 21 and is adapted to receive an ear 85 22, carried by the lower end of the ratchet-carrying member, the said pitman being pivotally connected to said ear by means of a pivot 23, the said ear being on a line with the double crank when the same is in a horizon- 90 tal position, and the pitman is thus on a dead-center and will hold the pawl-carrying member in its locked position with the pawl engaging the ratchet-teeth of the disk, and thus pressure exerted upon the pawl cannot 95 move the pawl-carrying member. The shaft 17 extends beyond the bearing 15 and has secured thereon the operating-lever 24, which extends in a direction opposite to that of the crank, but parallel therewith. The U- 100 shaped frame is provided with an outwardly-extending lug or arm 25, which is in the path of travel of the lever 24 and limits the forward and downward movement thereof.

From the foregoing description it will be 105 seen that when the lever 24 is down upon the lug the pitman is on a dead-center, and thus the pawl-carrying member is locked with the pawl engaging the ratchet-disk, as shown in Fig. 3. This position allows of the ready rotation of the brake-operating shaft the same as with the ordinary brake now in use.

When it is desired to release the brake-shaft, the lever 24 is drawn upwardly, throwing the pitman off of dead-center, and the continued movement of the lever moves the pawl-carrying member rearwardly, carrying with it the pawl, thus releasing the brake-shaft. The movement of the pawl-carrying member when releasing the brake is in the same direction as the force of the ratchet-disk is on the pawl, thus making the releasing of the brake-lever easy. The force of the ratchet-disk if strong enough would move the pawl-carrying member rearwardly after the pitman is thrown off of a dead-center.

Having thus fully described my invention, what I claim as new, and desire to secure by Letters Patent, is—

1. The combination with a rotary brake-operating shaft, a ratchet-disk carried thereby, of an intermediately-pivoted pawl-carrying member, a pawl carried by the upper end of the member and engaging the ratchet-disk, and means carried by the lower end of said member for rocking the same.
2. The combination with a rotary brake-operating shaft, a ratchet-disk carried thereby, of a pivoted pawl-carrying member, and an intermediately-pivoted weighted pawl carried by said member.
3. The combination with a rotary brake-operating shaft, a ratchet-disk carried thereby, of an intermediately-pivoted pawl-carrying member, an intermediately-pivoted weighted pawl carried by the upper end of said member, and means carried by the lower end of the pawl-carrying member for operating the same.
4. The combination with a rotary brake-operating shaft, a ratchet-disk carried thereby, of an intermediately-pivoted pawl-carrying member, an intermediately-pivoted pawl having one end weighted and holding the opposite end in engagement with the ratchet-disk, a double crank adjacent to and in a line with the lower end of the pawl-carrying member, and a pitman connected to said crank and pawl-carrying member, said pitman being on a dead-center when the pawl is engaging the ratchet-disk.
5. The combination with a rotary brake-

operating shaft, a ratchet-disk carried thereby, of an intermediately-pivoted pawl-carrying member, an intermediately-pivoted pawl having one end weighted and holding the opposite end in engagement with the ratchet-disk, a double crank adjacent to and in a line with the lower end of the pawl-carrying member, a pitman connected to said crank and pawl-carrying member, said pitman being on a dead-center when the pawl is engaging the ratchet-disk, an operating-lever carried by the crank in a line therewith, and means for limiting the movement of said lever when the pitman is on a dead-center.

6. The combination with a rotary brake-operating shaft, a ratchet-disk carried thereby and having teeth on its lower face, of a frame adjacent to said shaft, a pawl-carrying member intermediately pivoted within said frame, a pawl intermediately pivoted within the upper end of said member below the ratchet-disk, a weight carried by one end of the pawl for holding the opposite end upwardly in engagement with the ratchet-disk, and a wedge-shaped guide carried by the frame and adapted to hold and guide the pawl to the ratchet-teeth of the disk.

7. The combination with a brake-operating shaft having a ratchet, of a movable pawl-carrying member, and a pawl carried by said member and adapted to be moved in or out of engagement with the ratchet-disk.

8. The combination with a brake-operating shaft having a ratchet-disk, of a movable pawl-carrying member, a pawl carried by said member and adapted to be moved in or out of engagement with the ratchet-disk, a double crank adjacent said movable member, a pitman connected to the pawl-carrying member and to the crank in such a manner that the pitman is on a dead-center when the pawl is engaging the ratchet-disk.

In testimony whereof I have signed my name to this specification in the presence of two subscribing witnesses.

ANDREW MILLER.
